UNITED STATES PATENT OFFICE

HARRY GLAENZER, OF PHILADELPHIA, PENNSYLVANIA

SMOKE BOX FOR LOCOMOTIVES

Application filed October 17, 1929. Serial No. 400,243

My invention relates to certain improvements in smoke boxes for "Mallet" locomotives.

The object of my invention is to make the lower portion of the smoke box in an integral casting, combining a number of detail connections in the casting, making a smoke box of this type more economical in construction and maintenance.

10 In the accompanying drawings:

Fig. 1 is a side view illustrating my improved bottom section of a smoke box, the balance of the smoke box being shown in dotted lines as well as certain pipe connections; and

15 Fig. 2 is a sectional view on the line 2—2, Fig. 1.

Referring to the drawings, 1 is the smoke box of a locomotive of the "Mallet" type in the present instance. The lower portion 2 of the smoke box is made as an integral casting, while the portion 3 is of sheet metal, in the present instance secured to the lower portion by either a lap joint as shown in Fig. 2 which may be riveted or welded to the flange 4 of the casting 2, or a butt joint may be used, the two parts being welded together. The entire smoke box is joined to the boiler shell 5 in any suitable manner.

20 Made integral with the smoke box casting 2 is a bearing pad 6 which carries the weight of the forward end of the boiler and smoke box, and this bearing pad rests on the forward unit of the "Mallet" type locomotive. The detailed construction of this pad will vary with the particular design of locomotive to which the invention is applied.

At each side of the lower cast metal section of the smoke box is a steam pipe elbow 7 made integral with the section 2 and to which the usual steam pipes in the smoke box are attached. Connected to the outer end of each elbow 7 is a steam pipe 7^a leading to the rear unit of the locomotive.

25 The exhaust pipe elbows 8 at each side of the smoke box are also cast integral with the cast smoke box structure. The exhaust from the rear unit of the locomotive passes through the pipes 8^a and elbow 8 and delivers the same to the rear passage 9 of a double nozzle. 10

is an exhaust pipe connection made integral with the smoke box casting. In the present instance it is a ball-and-socket connection and is coupled to a pipe 10^a leading to the cylinder structure of the forward section of 55 the "Mallet" locomotive and delivers the exhaust steam to the forward passage 11 of the stack.

12 in an elbow which is made integral with the smoke box structure and is arranged to 60 be connected with a pipe leading to the forward feed water heater and communicates with the passage leading from the forward nozzle structures. The forward portion 13 of the smoke box is flattened as clearly shown 65 in Fig. 2, and is elevated so as to provide room over the running gear for an exhaust pipe and other details.

It will be seen by the above-described invention that by making the lower portion of 70 the smoke box of a "Mallet" locomotive as an integral casting, the elbows 7, 8 and 12 and the connection 10, and other similar attachments, which were heretofore made as separate parts bolted to the smoke box, are now 75 made integral with the smoke box structure, which not only makes a substantial structure but considerably reduces the cost of manufacture and maintenance.

By making the lower portion of the smoke 80 box structure in an integral casting, the bottom section of the smoke box can be flattened without difficulty, so as to raise the front portion a sufficient distance to provide room over the running gear for exhaust pipes and other 85 connections.

I claim:

1. The lower section of a smoke box of a "Mallet" locomotive made as an integral casting, the forward portion of which is flattened 90 and raised above the rear portion; and an integral bearing pad formed on the rear portion of the smoke box.

2. The lower section of a smoke box of a "Mallet" locomotive made as an integral casting, the forward portion of which is flattened 95 and raised above the rear portion; an integral bearing pad formed on the rear portion of the smoke box; and an exhaust pipe connection projecting from the underside of the flattened 100

portion of the said smoke box and made integral therewith and forming a passage for exhaust steam from the forward unit of the locomotive to the forward passage of the stack within the smoke box.

- 5 3. A smoke box structure made in two parts for a "Mallet" locomotive, the lower part being an integral casting and at its forward end being flattened and raised above the rear end; integral steam and exhaust elbows projecting from each side of the smoke box structure and cast integral with the lower section; an exhaust pipe ball-and-socket connection for the forward unit of the engine projecting from the flattened portion; an exhaust feed elbow also projecting from the flattened portion back of the exhaust pipe ball-and-socket connection; and an integral bearing pad depending from the rear portion of the said structure.
